(57) **CLAIM**

The ornamental design for a curved frame bench, substantially as shown and described.

DESCRIPTION

FIG. 1 is a front perspective view showing a curved frame bench according to my new design;

FIG. 2 is a right side elevation view thereof, the left side elevation being identical and opposite;

FIG. 3 is a rear elevation view thereof;

FIG. 4 is a top plan view thereof;

FIG. 5 is a front elevation view thereof; and,

FIG. 6 is a bottom plan view thereof.

The broken lines indicating seat and back structure shown in the drawings are for illustrative purposes only and form no part of the claimed design.
